POTTERY KILN

Filed Dec. 20, 1927

2 Sheets-Sheet 2

UNITED STATES PATENT OFFICE.

ALBERT C. WARD, OF CANONSBURG, PENNSYLVANIA.

POTTERY KILN.

Application filed December 20, 1927. Serial No. 241,322.

My invention relates to pottery kilns and has for its primary object to provide a heating system for the floor thereof adapted to uniformly transmit the heat to all parts beneath the floor so that the temperature thereof throughout its entire area will be uniformly maintained. The equal distribution of the heat beneath the pottery floor of the kiln is an important feature in the drying of pottery or the like in order that the entire output of a kiln may be uniformly dried and hardened.

Another object of the invention is to provide a series of spaced tiers circularly arranged beneath the pottery floor forming a support for the same, said tiers being disposed in staggered relation whereby to deflect the heat and to cause the same to circulate beneath the pottery floor in all directions and also to provide a radially disposed flue extending inwardly toward the center flue of the kiln from each of the fire boxes for the purpose of forming a relatively free passageway, of substantially slight area in order to provide a suitable draft for the fuel in the fire box.

A further object of the invention is to provide a double pottery floor for the kiln, with both the upper and lower sections thereof formed of brick of suitable dimensions enabling the same to be supported upon the tiers beneath the floor without employing the use of mortar or other binding material whereby to enable any portion of the floor to be easily and quickly removed for the purpose of repairing the same.

Other objects and advantages reside in the special construction and combination of the various elements comprising the invention, reference being had to the accompanying drawings, forming a part hereof, wherein:

Figure 1 is a side elevational view of the kiln with parts broken away and in section so as to illustrate the interior construction thereof,

Figure 2 is a top plan view of the pottery floor, with parts broken away illustrating the arrangement of the supporting tiers and

Figure 3 is a fragmentary vertical sectional view through a portion of the kiln taken substantially along a line 3—3 of Figure 2.

Referring now to the drawings in detail,

I have shown my invention comprising a pottery kiln of a type generally employed for the use in drying and hardening of pottery or the like and comprising an annular kiln construction composed of side walls 6, a base 5 and with a crown roof 7 supported by the walls and provided with the usual vent holes 8.

Upon the base of the kiln I provide a plurality of rows of tiers 9, circularly arranged in spaced relation, the tiers of each row being disposed in staggered relation with respect to the tiers of the adjacent row so that tortuous passages are formed therebetween. Each of the tiers preferably comprises a built up section of fire bricks, any suitable number of the tiers being provided depending upon the particular size of the kiln.

At spaced intervals about the wall 6 I arrange fire boxes 10, which as more clearly illustrated in Figures 1 and 3 of the drawings have their faces disposed at a horizontal plane beneath the base 5 and are provided with feed openings 11 formed in the wall of the kiln enabling the fuel to be placed in firing position within the fire boxes. A radially extending partition 12 is supported upon the base 5, the outer end of each of said partitions being disposed substantially midway of the sides of the fireboxes 10. The partitions 12 are constructed similarly to the tiers 9, that is being formed of fire brick and arranged with the side edges of the partition spaced slightly from the adjacent ends of the respective rows of tiers so as to form a passageway at each side of the partition extending toward the center of the kiln, the area between the pair of partitions substantially forming a flue with the partitions constituting the sides thereof. The inner end of each of the flues terminates short of the center of the kiln and inwardly therefrom are arranged additional circular rows of tiers as shown at 13 surrounding a row of radially disposed tapering tiers 14, circularly arranged to form a flue 15 at the center of the kiln. As illustrated in Figure 3 of the drawings the partitions 12 are provided with transversely disposed openings 16 providing for the free circulation of the heated air between each of the sections of the kiln formed by the radially extending partitions, the up-

per end of the openings terminating beneath the upper edge of the partitions whereby to prevent the passage of heated air at the extreme upper portion of the flues from one 5 to the other.

The tiers 9 and partitions 12 form supports for a double pottery floor composed of a subfloor section 17 and a top floor section 18, each of said floor sections being constructed of 10 fire brick, with the brick of the subfloor 17 being arranged in a circular formation and having their inner and outer edges upon adjacent rows of tiers.

In this manner each row of the bricks 15 comprising the subfloor 17 substantially forms a bridge above the respective rows of tiers 9 and by supporting the inner and outer edges of the brick comprising the floor in this manner, and as clearly illustrated in Figure 2 of the drawings, the floor may thus be constructed without employing the use of mortar or other binding material. It is understood that in constructing the floor in this manner that the inner and outer edges of each 25 brick must be curved in conformity with the curvature of the kiln.

The upper floor section 18 is likewise formed of fire brick and may be in the form of a square as shown in Figure 2 and spaced 30 upon the subfloor 17. The center of the floor section is provided with an opening forming the flue 15 and about which is disposed a sectional flue member 19 supported upon top of the tapered row of tires 14.

35 As illustrated in Figure 1 of the drawings the upper portion of the fire box, shown at 20, communicates with the space formed between the base 5 and the pottery floor and accordingly the heated air generated in the fire 40 box will be fed under the pottery floor and during its passage toward the flue 15 at the center of the kiln the portion thereof will circulate between the tiers 9 and the remainder will pass directly along the flues formed by 45 the partitions 12 to the flue 15 and thence upwardly into the chamber formed above the pottery floor.

The upper portion of the fire box is also 50 provided with a relatively small opening indicated at 21 extending through the floor section and about which openings are arranged bags 22 formed of vertically disposed wall sections supported upon the upper surface of the pottery floor without the opening 55 21, said bags having their upper portion open and communicating within the pottery chamber above the floor.

As will be seen from an inspection of Figure 1 of the drawing, the walls 6 of the kiln 60 above the crown 7 taper upwardly to form the stack 23.

The construction of the tiers 9 and partitions 12 in the manner indicated insures the circulation of the heated air throughout the 65 entire area beneath the pottery floor and thus

provides for the uniform heating thereof. The manner of staggering the tiers 9 prevents the passing of the heated air directly to the center flue 15 and thus serves to retain the heated air for a limited period beneath the 70 floor.

It is obvious that the invention is susceptible of various changes and modifications, without departing from the spirit or scope of the invention or sacrificing any of its advantages, and I accordingly claim all such forms of the device to which I am entitled. 75

Having thus described my invention, what I claim as new is:

1. In a pottery kiln of the class described, 80 a plurality of rows of supporting tiers arranged in circular formation in spaced relation, with the tiers of each row being staggered with respect to the tiers of the adjacent row, a plurality of radially extending flues extending transversely of the rows of tiers and separating said tiers into groups, said flues having transverse passages formed therein communicating with the groups of tiers at each side of the flue whereby to provide for the free circulation of air between the groups and a floor supported upon said tiers and said flues comprising a sub floor section and an upper floor section, said sub floor section being composed of a 95 plurality of associated units arranged in circular formation with their inner and outer edges resting upon two or more tiers of adjacent rows and said main floor section being composed of a plurality of units having their 100 edges disposed angularly with respect to the edges of said sub floor section.

2. In a pottery kiln of the class described comprising a circularly arranged wall having a plurality of fire boxes disposed at 105 spaced intervals therein, a plurality of supporting tiers arranged within the area defined by the wall, said tiers being disposed in rows arranged concentrically with respect to the wall with the tiers of each row disposed in staggered relation with respect to the tiers of the adjacent row, a radially disposed flue extending inwardly from each of said fire boxes and having transverse openings affording a circulation of air between the area at each side of the flues, said flues terminating short of the center of the kiln with a plurality of circularly arranged rows of tiers disposed inwardly thereof, said inner tiers being staggered with respect to the flues and with each other and a floor supported on said tiers and flues having a central flue providing communication between the air above and beneath the floor. 115

3. In a pottery kiln, a base having side walls extending upwardly therefrom, a plurality of fire boxes disposed in the wall and spaced at intervals, a radially extending partition extending inwardly from each of said fire boxes, a plurality of supporting tiers ar- 120 125 130

ranged within the area defined by the partitions and disposed in concentric rows with the tiers of each row staggered with respect to the tiers of each adjacent row, a floor supported on said partition and said tiers having a flue at its center portion providing an air passage above and below the floor, and pas-

sageways formed in said partition terminating below the floor, whereby to provide for the circulation of air at each side of the partitions adjacent the base end to restrict such circulation immediately beneath the floor. ¹⁰

In testimony whereof I affix my signature.

ALBERT C. WARD.
